TO PROGRESS MACHINE COMPANY, OF INDIANAPOLIS, INDIANA, A CORPORATION
OF INDIANA.

BOTTLE-CAPPING MACHINE.

1,134,676.

Specification of Letters Patent.

Patented Apr. 6, 1915.

Application filed August 21, 1913. Serial No. 786,030.

To all whom it may concern:

Be it known that we, JOHN J. GAYNOR and PETER CARL LIEBER, citizens of the United States, and residents of Indianapolis, county 5 of Marion, and State of Indiana, have invented a certain new and useful Bottle-Capping Machine; and we do hereby declare that the following is a full, clear, and exact description thereof, reference being had to the accompanying drawings, in which like 10 letters refer to like parts.

This invention relates to compensating mechanism in bottle crowning or capping machines, the object of said compensator being to allow bottles of varying lengths to be successfully crowned or capped. The bottle rest has a uniform stroke in applying the cap to the head.

Heretofore compensating devices in such 20 machines have had springs in them. On account of the varying action of springs from time to time, for well known reasons, the action of spring controlled compensators is not uniform.

The object of this invention is to do away with the springs in compensating devices and make such devices so that their actions will be uniform at all times, for different lengths of bottles.

The chief feature of the invention consists 30 in a pair of interlocking members with inclined engaging surfaces, one of said members being secured to the bottle support and the other weighted, and an inclined brace 35 plate for forcing the weighted member against the bottle supporting member, so that when the strain on the bottle support becomes too great, it will yield downward, forcing the weighted member and brace 40 plate sufficiently away to permit such action.

The full nature of the invention will be understood from the accompanying drawings and the following description and claims.

In the drawings, Figure 1 is an elevation 45 of a bottle capping machine with the parts broken away and with the casing in central vertical section. Fig. 2 is a section on the line 2—2 of Fig. 1 on an enlarged scale and 50 with the parts broken away intermediate their ends and also broken away at the bottom and showing the parts in normal position. Fig. 3 is the same showing the parts in actuated position. Fig. 4 is a perspective

view of the brace plate. Fig. 5 is a cross 55 section on the line 5—5 of Fig. 2.

The drawings herein illustrate a type of bottle capping machine which is now in practical use and which has a base 10 and casing 11 with a driving shaft 12 and driving pinion 13 meshing with a driving gear 14 for turning the bottle supports and which causes the rotation of an annular series of tubular bottle supports 15.

16 is a table through which the bottle supports reciprocate.

17 is a column for carrying the crowning head mechanism 18.

20 is a bottle in position to be crowned.

All of the foregoing mechanism is old and 70 constitutes no novel part of this invention excepting the particular construction of the bottle support in connection with the improvement herein.

The invention is illustrated in Fig. 2. 75 The bottle support 15 is a tube having within it a transverse disk or plate 21 on which the bottle rests and which is secured to the tube 16 by a screw 22. The bottle supporting tube 15 surrounds and telescopes on the 80 upper end of a compensator tube 23. Each tube 23 has a vertical opening 24 in one side thereof closed by a removable plate 25. The side walls of the tube 23 at the opening 24 are formed parallel with each other, as 85 shown in Fig. 5.

The bottle supporting plate 21 has secured to it a bar 26 which extends down within the tubes 15 and 23 and lies against the inner wall of the tube 23 and opposite 90 the opening 24 and beside said opening is recessed to receive a friction plate 27 which is secured therein by pins 28. The outer surface of said plate 27 has outwardly projecting shoulders 29 inwardly beveled at their lower 95 ends at 30. Another friction plate 31 which is here called the "weighted" plate because it has a weight 32 on the lower end lies against the friction plate 27, and the adjacent surface of plate 31 is formed with recesses 33 adapted to receive snugly the projections 29 and at the lower end of each recess 33 there is an inclined shoulder 34 against which the inclined lower end of the projection 29 bears. The outer side of the 100 plate 31 has in it a notch 35 into which a projection 36 on the upper end of the brace plate 37 extends loosely. The plate 37 is

placed in an inclined position with a projection 38 on its lower end entering a notch 39 in the wall of the tube 23, which is immediately above a block or plate 40 secured to the inner wall of said tube for the purpose of preventing the downward escape of the lower end of plate 37. The lateral shoulders 41 on the plate 37 bear against the friction plate 31 while the lateral shoulders 42 of plate 37 bear against the inner surface of the tube 23.

For lubricating the mechanism the tube 23 is closed by a disk 45 so that lubricating oil may be maintained in said tube and there are inclined oil conduits 46 through the bar 26 so that oil can pass and lubricate the adjacent surface of the bar 26 and the tube 23.

The operation is as follows: The angular position of the brace plate 37 bearing against the friction plate 31 will cause normally the plates 31 and 27 to remain interlocked, as shown in Fig. 2, and the weight 32 will coöperate in this regard and also in maintaining the inclined position of brace plate 37. While the bottle is being capped, it rests upon the disk 21 and if the downward strain thereon becomes excessive, the friction plate 27 will slip downward, as shown in Fig. 3, by reason of the beveled surfaces or shoulders 30 and 34. Therefore, when bottles varying in size are being capped, this means for supporting the bottles will allow for said variations in size. The frictional engagement between the two plates 27 and 31, after the plate 27 starts downward, is still so great that it will prevent any sudden downward movement of the bottle support and, therefore, the contents of the bottle will not be agitated by the machine during the capping. When the friction plates are in the position shown in Fig. 3, considerable friction between them is still maintained because of the inclined position of the brace plate 37, causing friction between plates 31 and 27.

Since the tube 15 by reason of a shoulder 50 thereon is limited in its downward movement at the end of its capping process, as soon as a roller 51 passes down on a cam track 52, the weight of the tube 23 will move the friction plate 31 down into interlocking engagement with the friction plate 27 and place them in normal position with relation to each other and then thereafter when the cam rides up on the cam track 52, the tube 23 will elevate the tube 15 and all of the parts connected therewith as a union.

The construction is such that the mechanism is accessible through plate 25. After removing the plate 25, the brace plate 37 can be moved laterally out of position and the friction plate 31 removed or replaced. There is practically no wear on the ends of the brace plate 37 because of the end thrust and if it were worn, it would be readily re-

placed. The brace plate 37 should be at an angle of less than forty-five degrees with relation to the wall of the tube 23 or more than forty-five degrees with relation to the friction plates 27 and 31.

The invention is:

1. A bottle capping machine including a bottle support, a friction plate secured thereto, a coöperating friction plate, and means for forcing said last-mentioned friction plate against the first-mentioned friction plate and arranged at an inclination to the direction of movement of said first-mentioned friction plate.

2. A bottle capping machine including a bottle support, a vertically disposed friction plate connected therewith, another friction plate adjacent said first-mentioned friction plate, said two friction plates having interlocking surfaces inclined at the lower edges thereof, and means for forcing said friction plates against each other.

3. A bottle capping machine including a bottle support, a bar extending downwardly therefrom with a recess in one side thereof, a friction plate insertible in said recess, another friction plate adjacent said first-mentioned friction plate, said two friction plates having interlocking surfaces inclined at the lower edges thereof, and means for forcing said friction plates against each other.

4. A bottle capping machine including a tubular bottle support, a tube on which said bottle supporting tube telescopes, a bar secured to the bottle support and extending down into the lower tube and bearing against the inner surface thereof, a friction plate carried by said bar, another friction plate adapted to be engaged by the plate carried by said bar, and means acting between the wall of said lower tube and said last-mentioned friction plate for forcing it against the first-mentioned friction plate.

5. A bottle capping machine including a tubular bottle support, a tube on which said bottle supporting tube telescopes, a bar secured to the bottle support and extending down into the lower tube and bearing against the inner surface thereof, a friction plate carried by said bar, another friction plate adapted to be engaged by the plate carried by said bar, and a plate arranged at an inclination between and engaging the last-mentioned friction plate and the inner surface of the lower tube.

6. A bottle capping machine including a tubular bottle support, a tube on which said bottle supporting tube telescopes, a bar secured to the bottle support and extending down into the lower tube and bearing against the inner surface thereof, a friction plate carried by said bar, another friction plate adapted to be engaged by the plate carried by said bar, a plate arranged at an inclination between and engaging the last-

mentioned friction plate and the inner surface of the lower tube, and a weight constantly acting on said last-mentioned friction plate.

- 5 7. A bottle capping machine including a tubular bottle support, a tube on which said bottle supporting tube telescopes, a bar secured to the bottle support and extending down into the lower tube and bearing 10 against the inner surface thereof, a friction plate carried by said bar, another friction plate adapted to be engaged by the plate carried by said bar, said friction plates having interlocking surfaces which are beveled 15 along their lower edges, a plate arranged at an inclination between and engaging the last-mentioned friction plate and the inner surface of the lower tube, and a weight constantly acting on said last-mentioned friction plate.
- 20 8. A bottle capping machine including a tubular bottle support, a tube on which said bottle supporting tube telescopes, a bar secured to the bottle support and extending 25 down into the lower tube and bearing against the inner surface thereof, a friction plate carried by said bar, another friction plate adapted to be engaged by the plate carried by said bar, a brace plate inclined 30 at less than forty-five degrees from the wall

of the lower tube and with its lower end engaging a notch in said lower tube and its upper end a notch in said last-mentioned friction plate, and a weight constantly acting on said last-mentioned friction plate. 35

9. A bottle capping machine including a tubular bottle support, a tube on which said bottle supporting tube telescopes, a bar secured to the bottle support and extending down into the lower tube and bearing 40 against the inner surface thereof, a friction plate carried by said bar, another friction plate adapted to be engaged by the plate carried by said bar, a plate arranged at an inclination between and engaging the last- 45 mentioned friction plate and the inner surface of the lower tube, a weight constantly acting on said last-mentioned friction plate, said lower tube having an opening beside said friction plates, and a removable plate 50 for closing said opening.

In witness whereof we have hereunto affixed our signatures in the presence of the witnesses herein named.
